UNITED STATES PATENT OFFICE.

ROBERT H. ELLIOTT, OF MEMPHIS, TENNESSEE.

HYDRAULIC EXCAVATOR.

SPECIFICATION forming part of Letters Patent No. 371,561, dated October 18, 1887.

Application filed August 19, 1886. Serial No. 211,284. (No model.)

To all whom it may concern:

Be it known that I, ROBERT H. ELLIOTT, of Memphis, in the county of Shelby and State of Tennessee, have invented a new and Improved 5 Hydraulic Excavator; and I hereby declare the following to be a full, clear, and exact description of the same, reference being had to the accompanying drawings, making part of this specification, in which—

10 Fig. 1 is a sectional view of a cylinder being sunk and my improved excavator applied to remove the material. Fig. 2 is a sectional view of a caisson, showing the same. Fig. 3 is an elevation, on an enlarged scale, of 15 the lower portion of the excavating-pipes. Fig. 4 is a section on the line *y y* of Fig. 3. Fig. 5 illustrates gratings to be used across the mouth of the receiving end of the discharge-pipe. Fig. 6 is an elevation of the lower end 20 of a modification of my excavator to be used with fine material. Fig. 7 is a cross-sectional view on the line *x x* of Fig. 6.

My invention relates to the removal of earth, silt, and other materials from the interior of 25 iron cylinders, caissons, and like structures to receive bridge-piers.

My invention also relates to dredging generally.

My invention consists in the novel construction and combination of devices, as will be 30 hereinafter more particularly described and specifically claimed.

In order that those skilled in the art may make and use my invention, I will proceed to 35 describe the exact manner in which I have carried it out.

In the said drawings, *A* is a depending water-conveying pipe, curved at its lower end and terminating in a contracted nozzle, *C*. Connected 40 to pipe *A*, and secured to it by braces *W*, if desired, is an exit or discharge pipe, *N*, having a large ingress-opening, *B*, lying op-

posite to the nozzle *C*. The upper end, *D*, of the discharge-pipe terminates at a point where it is desired to deposit the excavated material. 45

To the upper end of pipe *A* is attached a force-pump or some analogous device to force water down said pipe under a heavy head or pressure, and this stream flows from the contracted nozzle *C* toward and into the discharge-pipe *N*. As the stream passes from nozzle *C* into the mouth *B* of the discharge-pipe, it picks up any intervening earthy or other matters susceptible of being carried by the stream and carries them with the stream out through 50 the discharge-pipe. The lower ends of the pipes are advanced or changed in position to bring the stream successively upon different points of the material to be removed.

If the exigencies of the case warrant it, I 6 place across the mouth of the discharge-pipe gratings *A' B'*, as seen in Fig. 5, to prevent the entrance into the discharge-pipe of material so large as not to be easily discharged.

In Figs. 6 and 7 I show a modification of 6 my invention specially adapted for use in removing silt or other fine material. In this modification I join the entrance and exit pipe, leaving a cut-away portion, *S*, into which the fine material is drawn. 7

Having thus described my invention, what I claim as new, and desire to secure by Letters Patent, is—

The combination, with the pipes *A* and *N*, the former having the contracted nozzle *C*; and the latter the gratings *A' B'*, of the braces *W*, the whole constructed, arranged, and operated substantially as described, and for the purposes set forth.

ROBERT H. ELLIOTT.
